UNITED STATES PATENT OFFICE.

JOSEF PEACH, OF TRAVERSE CITY, MICHIGAN.

MITER-BOX.

No. 845,571.

Specification of Letters Patent.

Patented Feb. 26, 1907.

Application filed December 13, 1905. Serial No. 291,551.

To all whom it may concern:

Be it known that I, JOSEF PEACH, a citizen of the United States, and a resident of Traverse City, in the county of Grand Traverse 5 and State of Michigan, have invented a new and Improved Miter-Box, of which the following is a full, clear, and exact description.

The invention relates to wood-sawing, and its object is to provide a new and improved 10 miter-box arranged to permit of cutting the wood or other material at any desired angle and without changing the position of the saw in the saw-guides.

The invention consists of novel features 15 and parts and combinations of the same, which will be more fully described hereinafter and then pointed out in the claims.

A practical embodiment of the invention is represented in the accompanying drawings, forming a part of this specification, in 20 which similar characters of reference indicate corresponding parts in all the views.

Figure 1 is a perspective view of the improvement. Fig. 2 is a plan view of the 25 same. Fig. 3 is a sectional side elevation of the same on the line 3-3 of Fig. 2, and Fig. 4 is an inverted plan view of part of the improvement. Fig. 5 is a detail perspective view of the work-guides and the pivotal connection with the base.

On a suitably-constructed base A is arranged a pivot-pin B, on which is mounted to turn a platform C, carrying saw-guides D, between which the saw is inserted for cutting 35 the wood or other material at a desired angle. The platform C is normally held against turning by the use of a screw E, extending through a lug A', rising from the base A, the screw engaging a lug C', depending from the under 40 side of the platform C. Thus when the screw E is in position, as shown in Fig. 3, the platform C is held against turning; but when the screw E is unscrewed then the platform C may be turned, if desired. On the pivot B 45 are also mounted to swing work-guides F and F' in radial alinement with the pivot B and extending on opposite sides of the saw-blade in the saw-guide D, which latter also is radial relative to the pivot B, as will be readily understood by reference to Fig. 2. Each of the 50 work-guides F and F' is provided with a foot F², adapted to travel on the upper surface of the base A, and each foot F² is adapted to abut against the free end of a stop G, prefer- 55 ably in the form of a spring-tongue secured to the base A within a recess formed in the top

of the said base. The stops G are placed in such position on the base A that when a foot F² abuts against the free end of the stop then the corresponding work-guide F or F' is held 60 at an angle to the saw-blade, preferably at an angle of either forty-five degrees or ninety degrees, as will be readily understood by reference to Fig. 2. The work-guides F F' are slotted to receive the platform C and are connected by arms F^x F^y with rings F^v F^w, journaled on the pivot-pin B. The work-guides F and F' are pivotally connected by links H and H' with a slide I, mounted to slide in suitable guideways J, formed on the under 70 side of the base A and arranged radially relative to the pivot B and lengthwise of the saw held in the saw-guide D. The links H and H' extend through elongated slots A², formed in the base A, and the said links are bent to 75 extend with their forward ends above the base A and then pass downward through the slots A² to connect with the slide I. On the latter is secured a rod I', passing through one 80 end of the base A and carrying at its outer terminal a knob I², adapted to be taken hold of by the operator for pushing the slide I inward or outward with a view to swing the work-guides F and F' forwardly or backwardly until the work-guides assume the desired position according to the miter to be 85 cut on the stick of wood or other material to be mitered.

It is understood that the work is placed against one of the work-guides F or F' to 90 cut either a right or left hand miter by the use of the saw guided in the saw-guides D, it being also understood that the two work-guides F and F' move simultaneously on shifting the slide I and assume the same angle relative to the saw in the saw-guides D, but on opposite sides thereof. After the slide I has been moved to the desired position with a view to bring the work-guides F and F' to the correct position then the 100 slide I, and consequently the work-guides F and F', are locked in place by the use of a set-screw K, screwing in a nut A³, arranged on the under side of the base A, the inner terminal of the set-screw K abutting against 105 the rod I' of the slide I. (See Fig. 4.) The forward end of the saw held in the saw-guides D also passes through supplementary or auxiliary guides L, arranged on the front end of the base A.

As illustrated in the drawings, the saw-guides D are formed of two base-plates D',

provided with transversely-elongated slots D², through which extend screws D³, screwing in the platform C to allow of adjusting the saw-guides D toward and from each other 5 according to the thickness of the saw used in the miter-box. From each base D' rises a support D⁴, having its inner face beveled for receiving a correspondingly-shaped guiding member D⁵, adapted to be moved nearer 10 to or farther from the center of the pivot B. Each guide member D⁵ is adapted to be fastened in position on its support by a screw D⁶, passing through a lengthwise-elongated slot D⁷, formed in the corresponding support 15 D⁴, so that after a guide member D⁵ is moved in the desired position then it can be fastened in place on the corresponding support D⁴ by screwing up the screw D⁶.

Each of the work-guides F and F' is provided 20 with an adjustable member F³, engaged by a set-screw F⁴, extending through an elongated slot F⁵, formed in a vertically-disposed support F⁷, rising integrally from the base F⁶ of the work-guide F or F'. On 25 loosening the set-screws F⁴ the members F³ of the work-guides F and F' can be adjusted inward or outward relative to the center of the pivot B and when in an outermost position allow of passing the work across the platform C between the saw-guides and the work-guides, and hence the operator can now cut 30 inside miters or corners.

In using the device the saw is placed in 35 position in the guides D and L and the knob I² is moved inward or outward, so as to swing the work-guides F and F' simultaneously in the desired position, and then the work is placed against the member F³ of the corresponding work-guide F or F', after which the 40 saw is used to cut the work with a view to produce the desired miter.

The miter-box shown and described is 45 very simple and durable in construction and is arranged to allow of cutting accurately right and left hand miters at one adjustment and without requiring changing the position of the saw in the saw-guides D. When the 50 position of the saw-guides is changed, the saw is removed from the guides L, said guides being only used when the saw-guides are in parallelism therewith.

Having thus described my invention, I claim as new and desire to secure by Letters Patent—

55 1. A miter-box, comprising a saw-guide, work-guides mounted to swing from a center from which radiates the saw-guide, and man-

ually-controlled means for imparting a swinging movement to the said work-guides to simultaneously set the same alike relative to 60 and on opposite sides of the saw-guide, the saw-guide and the work-guides being provided with radially-adjustable plates, whereby to permit the insertion of different sizes of work.

2. A miter-box, comprising a saw-guide, work-guides mounted to swing from a center from which radiates the saw-guide, each work-guide having a radially-adjustable plate, and manually-controlled means for imparting a swinging movement to the said work-guides to simultaneously set the same alike relative to and on opposite sides of the saw-guide.

3. A miter-box, comprising a saw-guide 75 mounted to swing, means for normally holding the saw-guide against swinging movement, work-guides mounted to swing from a center from which radiates the saw-guide, and manually-controlled means for imparting a swinging movement to the said work-guides to simultaneously set the same alike relative to and on opposite sides of the saw-guide.

4. A miter-box, comprising a base, a saw- 85 guide mounted on the said base, work-guides mounted to swing on the said base, a slide mounted to slide on the said base in the direction of the length of the said saw-guide, links connecting the said work-guides with 90 the said slide, and means under the control of the operator for imparting movement to the said slide, said saw-guide and work-guides being provided with radially-adjustable plates whereby to permit the insertion of different 95 sizes of work.

5. A miter-box, comprising a base, a saw-guide mounted to turn on the said base, work-guides mounted to swing on the said base, a slide mounted to slide on the said base 100 in the direction of the length of the said saw-guide, links connecting the said work-guides with the said slide, means under the control of the operator for imparting movement to the said slide, and means on the said base for holding the said saw-guide normally against 105 turning.

In testimony whereof I have signed my name to this specification in the presence of two subscribing witnesses.

JOSEF PEACH.
